[57] CLAIM

The ornamental design for a heater fan, as shown and described.

DESCRIPTION

FIG. 1 is a perspective view of a heater fan showing the first embodiment of our new design;

FIG. 2 is a top plan view thereof;

FIG. 3 is a bottom view thereof;

FIG. 4 is a front elevational view thereof;

FIG. 5 is a right side elevational view thereof, the left side view being a mirror image thereof;

FIG. 6 is a rear elevational view thereof;

FIG. 7 is a perspective view of a heater fan showing the second embodiment of our new design, the sole difference from the first embodiment being the wood grain finish;

FIG. 8 is a top plan view of FIG. 7;

FIG. 9 is a bottom plan view of FIG. 7;

FIG. 10 is a front elevational view of FIG. 7;

FIG. 11 is a right side elevational view of FIG. 7, the left side view being a mirror image thereof; and,

FIG. 12 is a rear elevational view of FIG. 7.

The dot pattern fragmentarily shown in FIGS. 1-5 and 7-11, is understood to extend uniformly throughout the front panel. The two screen patterns fragmentarily shown in FIG. 6, and FIG. 12, are understood to extend uniformly throughout the areas represented.
